(57) CLAIM

The ornamental design for a double tissue holder, as shown and described.

DESCRIPTION

FIG. 1 is a perspective view of a double tissue holder showing my new design;

FIG. 2 is a front elevational view thereof;

FIG. 3 is a right end view thereof, the opposite end being a mirror image of the end shown; and,

FIG. 4 is a top plan view thereof, the opposite side being a mirror image of the side shown.
